UNITED STATES PATENT OFFICE.

LUCIEN C. MITCHELL, OF CHICAGO, ILLINOIS.

PARACHUTE AND PROCESS OF FOLDING THE SAME.

1,398,303.

Specification of Letters Patent. Patented Nov. 29, 1921.

Application filed October 21, 1920. Serial No. 418,437.

To all whom it may concern:

Be it known that I, LUCIEN C. MITCHELL, a citizen of the United States, and resident of Chicago, county of Cook, and State of Illinois, have invented certain new and useful Improvements in Parachutes and Processes of Folding the Same, of which the following is a specification, and which are illustrated in the accompanying drawings, 10 forming a part thereof.

The invention relates to parachutes and has as an object the provision of a device of this nature that will come into action when thrown over-board from an aeroplane 15 without danger of the weight supporting cords becoming snarled. A further object is the provision of a process of folding the parachute provided by the invention.

An illustrative embodiment of the invention is shown in the accompanying drawings in which—

Figure 1 is a side elevation of an expanded parachute;

Fig. 2 is a side elevation of a folded parachute;

Figs. 3 and 4 are detail side elevations of a cord pocket illustrating the mode of inserting the cord therein while folding the parachute;

Fig. 5 is a detail plan view of an inserting stick with cord in place;

Fig. 6 is a detail elevation of the structure of Fig. 5;

Figs. 7, 8 and 9 are perspective views 25 showing different forms of inserting sticks.

To lessen local strains on the fabric of the parachute the cords 10 are preferably placed on the outside of the cloth 11, as shown, in Fig. 1, and are arranged to run 40 continuously over the top of the vent 12, each cord having its two ends attached at opposite sides of the ring 13. To keep the cords in correct location they are secured to the fabric 11, as by passing under 45 straps 14.

To receive the cords when the parachute is folded, pockets 15 are shown, there being a pocket for each end of each cord. The cords are secured to the fabric by means of straps 14 in the interior of the pockets 15 and down to the edge of the fabric. The pockets are preferably closed at the tops 17 to prevent any turns of the coil of cord from escaping to cause a snarl.

The method of inserting the coiled cords in the pocket—provided by the invention

comprises coiling the cord on a suitable implement, inserting the implement and coil into the pocket and withdrawing the implement. Different forms of implement for the 60 purpose are shown in Figs. 7, 8 and 9. In its simplest form the implement comprises a stick 18 having a notch 19 in its top to prevent the cord slipping off.

To coil the cord on the stick, a length of 65 cord equal to the length of the pocket is measured off and the cord beyond the length is laid in the notch at the end of the stick and bound to the tip of the stick by several turns of the cord, as illustrated in Figs. 5 70 and 6. The tip of the stick and applied turns are then grasped by the hand of the operator and the cord is coiled on the stick by passing it around the butt of the stick until substantially the entire length of the 75 cord between the fabric and the ring 13 is coiled on the stick, in the manner shown in Fig. 3. The stick bearing the cord is then inserted in the pocket as shown in Fig. 4 and, holding the bottom of the coil by 80 grasping the outside of the pocket, the stick is withdrawn from the coil leaving it in the pocket. The stick is tapered sufficiently to render its withdrawal easy.

To increase the ease of withdrawal of the 85 inserting stick it may be made partially collapsible, as shown in Fig. 7, by a saw kerf 20 extending from the tip downward a substantial portion of its length. With this form of stick, later turns will press the 90 sides of the stick together, thus slightly loosening the earlier turns and making withdrawal of the stick easy. Another form of collapsible stick 21 may be formed of wire, as shown in Fig. 9. This form comprises 95 a piece of wire or rod bent on itself and a coil 22 formed on one end which is turned at an angle. The other end has an elbow 23 adapted to lie against the coil when the ends are pressed toward each other. When 100 the cord has been coiled on the wire and inserted in the pocket, the ends may be pressed together and the implement collapsed to secure ready withdrawal from the coils of the cord.

Since the cord is concentrated in the 105 pockets as near the mouth as possible, the delivery when the parachute is dropped, will take place with a minimum of friction upon the fabric. Moreover, as the cord leaves the 110 coil the location upon the edge of the parachute where it passes out of the pocket will

be shifted from side to side, thus distributing the friction and preventing burning of the fabric.

Minor changes may be made in the physical embodiment of the invention and in the steps of the method without departing from the spirit of the invention.

I claim as my invention:

1. A folded parachute comprising, the combination with the folded parachute body of tubular pockets radially arranged upon the parachute body adjacent the perimeter thereof, each pocket being open at its outer end, and shroud cords each extending from the perimeter of the body inwardly in substantially a straight line through one of the pockets to the inner end of the pocket and thence outwardly through the pocket in a helical coil substantially filling the pocket from its inner end to its said open outer end.

2. A folded parachute comprising the combination with the folded parachute body of tubular pockets radially arranged upon the parachute body adjacent the perimeter thereof, each pocket being open at its outer end, and shroud cords each extending radially outward over the parachute body from the center thereof to the inner end of one of the said pockets and through the pocket to the perimeter of the parachute body, thence inwardly through the same pocket to the inner end of the pocket and finally outwardly through the pocket in a helical coil substantially filling the pocket from its inner end to its said open outer end.

3. The method of packing the shroud

cords of a parachute comprising a body with the said cords extending from the perimeter of the body and tubular pockets open at their outer ends radially arranged upon the body adjacent its perimeter which consists in winding a part of each cord beyond a length of the same immediately adjacent the perimeter of the parachute body equal to the length of one of the said tubular pockets into a helical coil of substantially the length of the pocket and inserting the said length of each cord and the corresponding helical coil into the pocket through its open end with the free end of the cord projecting from the said open end of the pocket.

4. The method of packing the shroud cords of a parachute comprising a body with the said cords extending from the perimeter of the body and tubular pockets open at their outer ends radially arranged upon the body adjacent its perimeter which consists in winding a part of each cord beyond a length of the same immediately adjacent the perimeter of the parachute body equal to the length of one of the said tubular pockets upon a stick to form upon the stick a helical coil of substantially the length of the pocket, inserting the stick with the cord wound thereon into the pocket through its open end thereby also drawing into the pocket the said length of cord which is immediately adjacent the perimeter of the parachute body, and withdrawing the stick from the pocket and the said helical coil.

LUCIEN C. MITCHELL.
